CLAIM

The ornamental design for a swimming pool, as shown and described.

DESCRIPTION

FIG. 1 is a front, left and top perspective view of a swimming pool, showing my new design;

FIG. 2 is a rear, right and bottom perspective view thereof;
FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 shown in FIG. 1;
FIG. 10 is an enlarged view of portion 10 shown in FIG. 1;
and,FIG. 11 is an enlarged view of portion 11 shown in FIG. 2.
The consistent length broken lines shown in the drawings illustrate portions of the swimming pool that form no part of the claimed design. The alternating dot-dash lines in the drawings depict the boundaries of the enlarged portions and also form no part of the claimed design.**1 Claim, 11 Drawing Sheets**---
